UNITED STATES PATENT OFFICE

HERMANN LANG, OF NEW YORK, N. Y.

EYESHIELD

Application filed July 6, 1931. Serial No. 548,820.

This invention relates to eye shields in general, and particularly to what may be termed collapsible eye shields.

Eye shields are generally known to have been made in various designs, which are more or less effective and practical, however, their construction usually does not permit their safe handling, and their being carried about without great discomfort when not in use, due to their bulkiness.

The prime objects of my invention are to produce a very simple, easily transportable and readily useable, inexpensive device of this kind which may be easily inserted into a pocket or pocket-book, without discomfort to the person carrying it, and without taking up unduly much space, and which need not be handled too carefully for fear that it may be damaged while being carried in its collapsed form or inoperative position.

Another object of my invention is to provide an eyeshield which will afford ample protection against glare or excessive light and which has the advantage of consisting of a practically unbreakable frame and a practically unbreakable and readily foldable shield member, adapted to be associated with the frame when desired to be worn.

The foregoing and further objects will be more fully apparent from the following description and the accompanying drawings, forming part of my disclosure, but by no means intended to restrict my invention to the actual showing, and in which

Fig. 1 illustrates a plan view of a preferred form of my device.

Fig. 2 illustrates the shield member in its blanked-out or developed form.

Fig. 3 is a plan view of the finished shield member, and

Fig. 4 illustrates a modified form of my eye shield frame.

Referring now to the drawings, numeral 10 denotes the front portion of the shield frame, which is preferably bowed outwards, that is, in such a way as to project beyond the forehead and above the eyebrows of the wearer, and which is provided with hinge-forming ends 11, to which are connected head attaching members 12. The latter are so

shaped that their connecting ends 13 are curved inwards, from connecting point 11, the purpose of which curved connecting ends will be explained presently.

Referring now to Figures 2 and 3, there will be seen a shield member 14 which is preferably made of highly elastic rubber tissue. The preferred way of producing this shield member consists of cutting or blanking-out from a rubber sheet a form shown in Figure 2, which consists of two symmetrical halves 15, provided with a central opening 16. These halves are folded, along lines 17, against one another, so that their outer edges may be cemented into a sack-shaped form as illustrated in Figure 3.

It will be seen that by constructing the eye shield member in the above stated way, there are formed closed ends or pockets 18, between which two ends the open portion, corresponding to cut-out 16, remains available for inserting therethrough the frame of the eye shield. It is obvious, of course, that the eye shield may be constructed in any other suitable manner, as for instance in the shape of a relatively wide rubber band, or in any other practical way.

Reverting again to Figure 1, there will be seen (in comparing the size of shield member 14 in that figure with the size shown in Figure 3) that the eye shield member in the former figure is expanded, and consequently under tension. It will also be observed that the closed ends or pockets of the eye shield member engage and cover the hinged end portions of frame member 10 and the curved connecting ends 13 of the attaching members. By so engaging the latter, the resiliency of the material will exert a pressure against the attaching members, causing them normally to assume a collapsed position, as shown in broken lines in Fig. 1. When the device is intended to be used, attaching members 12 are placed into the position shown in full lines in Fig. 1, and the shield member will exert a slight pressure against these members, thereby facilitating the holding of the shield device against the head of the wearer. When the device is not in use, shield member 14 may be removed from or retained

with the frame, in which latter case the head attaching members will be caused to revert to their collapsed position.

Due to its material and construction, shield member 14 is practically indestructible, and therefore no fear need be had as to its being damaged when worn in a pocket or elsewhere. On the other hand, in the event the shield member should become damaged by tearing, it may be readily replaced, since it is very inexpensive. The frame is preferably constructed of light material, as for instance aluminum, celluloid, or any other suitable matter, which due to its construction is also practically indestructible.

15 Referring to Figure 4, there will be seen a modified form of my shield frame, where a single wire construction is used, which is formed into a front portion 19, curved similarly to frame member 10, the ends of which, indicated at 20, are turned upon themselves and terminate in a coil or loop 21, from which extend head attaching arms 22.

20 In this construction the normal, inoperative position of the head attaching arms is that shown in full lines in Figure 4, while their operative position, when the device is in use, is shown in broken lines. The same rubber shield member, as described in connection with Figures 1, 2 and 3, is applied also to the modified frame form, and its operation is practically the same, except that the end pockets 18 are not required to bear against arms 22 for the purpose of closing them to an inoperative position.

35 There will be observed from Figure 1 that the open edge of the shield member is stretched between the attaching arms 12. This stretched part permits close accommodation of, and intimate contact between the shield member and any shape of a forehead to which it may be attached. This close fit between the shield member and the forehead has another very important advantage, in that it prevents perspiration from dropping into the shielded eyes, particularly at times when the device is used in extremely warm weather.

40 While I have shown and described specific forms of my idea, be it understood that improvements and variations may be incorporated therein, without departing from the broad scope thereof, as defined by the annexed claims.

45 I claim:

50 1. In an eye shade, a frame comprising an outwardly curved front member provided with hinge ends, a pair of head attaching members operatively connected with the hinge ends of said front member and provided with inwardly directed connecting arms, a shield member made of a substantially closed rubber sack, having end pockets, slipped over the front member, and engaging its ends and the connecting arms of said at-

taching members with said pockets, the portion of said shield member between said pockets being open to permit the insertion of said frame therein.

55 2. The combination with an eye shield, of a shield member, comprising a substantially closed rubber sack having end pockets and a curved, closed front edge, and an open portion formed between said end pockets.

60 In testimony whereof he affixes his signature.

70 HERMANN LANG.
